RAILWAY TRAFFIC CONTROLLING
APPARATUS

Howard A. Thompson, Edgewood, Pa., assignor to
The Union Switch & Signal Company, Swiss-
vale, Pa., a corporation of Pennsylvania

Application April 6, 1940, Serial No. 328,327

13 Claims. (Cl. 246—45)

My invention relates to railway traffic controlling apparatus, and more particularly to apparatus for railway signal systems using coded energy of the time code type.

5 Railway signal systems using direct current coded at different codes each of which has a cyclic pattern consisting of one on and one off period have been proposed. The on and off periods of each code have distinctive pre-selected 10 durations, the polarity of the direct current being, however, either of positive or of negative polarity as may be more convenient. A code following relay of the neutral type is operated in step with the on and off periods of the code 15 to control slow acting decoding devices. Such decoding devices are proportioned for different slow acting periods and are responsive in different combinations according to the duration of the periods of the different codes, and in turn 20 selectively govern signaling circuits.

A feature of my invention is the provision of novel and improved means for a time code system wherein the different codes have a polarity characteristic. That is direct current at times 25 of positive polarity and at other times of negative polarity is coded at different time codes for selectively governing signaling circuits through decoding means which is selectively responsive to the polarity of the current as well as to the duration of the code periods.

Another feature of my invention is the provision of novel and improved apparatus of the type here contemplated wherewith the duration of the code periods for the different codes are 30 widely different and of durations such that a direct current polarized relay may be used as a code following relay to operate a neutral contact carrying armature in step with the code periods and to position a polar contact carrying armature at a normal or a reverse position according 35 to the polarity of the coded current.

A further feature of my invention is the provision in systems using time codes of novel and improved decoding means of simple and inexpensive construction.

Still another feature of my invention is the provision of novel and improved apparatus for a four-block five-indication signal system for railways.

50 The above features, as well as other advantages of my invention, are obtained by providing two coding elements operable at widely different rates. That is, one such element operates to code direct current at a relatively low rate to 55 create a time code pattern having relatively long on and off periods, and the other of such elements operates to code the current at a relatively high rate to create a time code pattern having relatively short on and off periods. A 60 pole changer is associated with such coding ele-

ments to pole change the circuit under selected control conditions with the result that the coded current is of positive or negative polarity according as said pole changer is set at one or the other of its two positions. Hence the coded current 5 has a polarity characteristic as well as distinctive time code pattern.

The code following relay which receives such coded current is a polarized relay of the type whose polar armature remains in the position to 10 which it was last moved when the relay is deenergized. The neutral contact carrying armature of such relay is therefore operated in step with the on and off periods of the particular code applied to the relay irrespective of the polarity of 15 the current, while the polar contact carrying armature of such relay is stationary at either the normal or reverse position according to the polarity of the coded current. That is the polar armature does not follow the on and off periods 20 but remains at the position to which it is moved at the start of the code as long as that code persists.

To distinguish between the relatively long and short code periods I provide a decoding transformer and a decoding relay proportioned for preselected characteristics. Direct current is alternately supplied to different portions of a primary winding of the decoding transformer over front and back neutral contacts of the code following relay to build up magnetic flux in the core of the transformer during each on and off period and which flux is opposite in direction for the on and off code periods. The decoding transformer and the associated charging circuit 30 are proportioned so that magnetic saturation of the core is effected during a short code period and hence the flux density built up in the core is not materially greater for the long code period than that effected for the short code period. It 35 follows that the electromotive force induced in the secondary winding of the decoding transformer due to the reversal of the magnetic flux caused by operation of the code following relay is substantially of the same value for both of these codes. The time interval between successive electromotive forces induced in the transformer secondary winding is in accordance with the duration of the on and off periods, being of a relatively short interval when the code following relay is operated by the code of the short on and off periods and being of a relatively long interval when the code following relay is operated by the code of the long on and off periods.

The decoding relay is connected to the secondary winding of the decoding transformer for energization of that relay by the electromotive force induced in the secondary winding. Preferably rectifying means is interposed in the connection of the decoding relay to the secondary 55 winding. The decoding relay is connected to the 60

winding and the relay is supplied with impulses of unidirectional current. The decoding relay winding and the transformer secondary winding are proportioned as to their impedances so that 5 the electromotive forces induced in the secondary winding in the manner described above cause the energization of the decoding relay to build up to a value sufficient to pick up the relay when the rate of occurrence of the electromotive forces 10 corresponds to that of the code having the short on and off periods but that when the rate of occurrence of the electromotive forces corresponds to the code having the long on and off periods the energization of the decoding relay created 15 by one electromotive force dies away before the next electromotive force appears and the decoding relay is not effectively energized and remains released. In other words, the decoding relay, the decoding transformer and the circuit associated therewith are proportioned so that when the 20 electromotive forces induced in the transformer secondary winding are time spaced apart by a short interval corresponding to the code of the short on and off periods, the decoding relay is effectively energized and picked up, but that 25 when the electromotive forces are time spaced apart by intervals corresponding to the code of the long on and off periods, the decoding relay is not effectively energized and is released. The 30 decoding relay is provided with a slow release period sufficient to bridge the short interval but not the long interval.

To further detect the presence of coded current I preferably use two slow release relays which 35 check the operation of the code following relay by one of such relays being controlled over a front neutral contact of the code following relay and by the other of such relays being controlled over a back neutral contact of the code following relay 40 and a front contact of the first mentioned of such relays.

Contacts of the decoding relay and polar contacts of the code following relay are used to 45 selectively govern signaling circuits, such circuits being also controlled preferably by the second mentioned check relay.

I shall describe one form of apparatus embodying my invention and shall then point out the novel features thereof in claims.

50 In the accompanying drawing, Fig. 1 is a diagrammatic view showing one form of apparatus embodying my invention when used for a four-block five-indication wayside signal system for railways. Fig. 2 is a diagram showing four different polar time codes that may be used with the apparatus of Fig. 1.

It will be understood that I do not wish to limit my invention to this one form of apparatus, and this one form will serve to illustrate the many 60 places where apparatus embodying my invention is useful.

Referring to Fig. 1, the reference characters 1a and 1b designate the track rails of a stretch of railway over which traffic normally moves in the 65 direction indicated by an arrow, and which rails are formed by the usual insulated rail joints into consecutive track sections of which sections only one section W-X and the adjoining ends of the two adjacent sections are shown for the sake of 70 simplicity since these are sufficient for a full understanding of my invention.

Each track section is provided with a track circuit comprising coded current supply means connected across the rails at one end of the section and a code following relay connected across 75

the rails at the other end of the section. These track circuits are all alike and a description of the track circuit for section W-X will serve for an understanding of all. The immediate source of coded current for the track circuit of section W-X is a battery XB and two relays XR and XP. When relay XP is picked up, closing front contacts 3 and 4, and relay XR is picked up closing front contact 5, the battery XB is connected across the rails adjacent the exit end of section 10 W-X and direct current is supplied to the track circuit, the current being of what I shall term positive polarity. When relay XP is released closing back contacts 6 and 7 and relay XR is picked up to close front contact 5, the battery 15 XB is connected to the rails and direct current is supplied to the track circuit but the current is of negative polarity since the connection is pole changed at back contacts 6 and 7 of relay XP. When relay XR is released to open front contact 5 20 the battery XB is disconnected from the rails and no current is supplied to the track circuit. Thus with relay XR operated according to a predetermined cycle consisting of a period in which the relay is picked up and a corresponding period in 25 which the relay is released, the current of the track circuit of section W-X has a cycle pattern corresponding to the cycle at which relay XR is operated. Such coded current is of positive polarity when relay XP is picked up and is of 30 negative polarity when relay XP is released. It follows that relay XP and XR are operable to code the track circuit current with different codes each of which has a polarity characteristic as 35 well as a distinct time code pattern.

Four different polar time codes that may be created by relays XR and XP are illustrated by the diagrams in Fig. 2, in which a flow of current of negative polarity is represented by the portions of a diagram below the base line and a flow of 40 current of positive polarity is represented by the portions of a diagram above the base line. Under a first or approach condition, relay XP is released and relay XR is operated at a rate of, say, 20 45 cycles per minute or once every three seconds, relay XR being picked up for substantially one and one-half seconds and released for substantially one and one-half seconds each operation cycle. Thus as illustrated in Fig. 2, an approach code has a cyclic pattern consisting of a 50 relatively long on and off period of one and one-half seconds each and a negative polarity characteristic. Under a second or approach-slow condition, relay XP is released as before and relay XR is operated at the rate of, say, 120 cycles per minute or two cycles per second, relay XR being 55 picked up for one-fourth second and released for one-fourth second each operation cycle. The approach-slow code hence has a cyclic pattern consisting of a relatively short on and off period of 60 one-fourth second each and a negative polarity characteristic. Under a third or approach-medium condition, relay XP is picked up and relay XR is operated at the rate of 20 cycles per minute. The approach-medium code consists, 65 therefore, of a cyclic pattern having relatively long on and off periods and a positive polarity characteristic. Under a fourth or clear condition, relay XP is picked up and relay XR is operated at the rate of 120 cycles per minute, and the clear 70 code has a cyclic pattern of relatively short on and off periods and a positive polarity characteristic. The manner of controlling relays XP and XR to effect the different polar time codes of Fig. 2 will appear hereinafter.

At the left-hand end of Fig. 1 there are shown a battery WB and relays WP and WR which function to supply coded current to the track circuit of the section next in the rear of section 5 W—X in the same manner the battery XB and relays XP and XR function to supply coded current to the track circuit of section W—X.

It is to be observed in connection with the codes of Fig. 2 that the code rate of 20 cycles per 10 minute is a relatively low rate creating a code having long on and off periods and the code rate of 120 cycles per minute is a relatively high rate creating a code having short on and off periods. It is to be understood, of course, that my invention 15 is not limited to these specific code rates but such rates are satisfactory and are used to illustrate the invention.

The code following relay for the track circuit of section W—X is a relay CF whose winding 8 is connected across the rails adjacent the entrance end of the section over wires 9 and 10. Relay CF is a direct current polarized relay of the type whose polar armature remains in the position to which it was last moved when the relay is de-25 energized. When current is supplied to the track circuit during an on period of a code and winding 8 of relay CF is energized, the front neutral contacts 11, 12 and 13 are closed and when no current is supplied to the track circuit during an off period of a code and winding 8 is deenergized, the back neutral contacts 14, 15 and 16 are closed, these neutral contacts of relay CF being thus operated in step with the on and off periods of the code impressed upon the track circuit current. 30 When the track circuit current is of positive polarity the normal polar contacts 17, 18, 19 and 20 are closed and when the current is of negative polarity the reverse polar contacts 21, 22, 23 and 24 are closed. During each off code period and 35 relay CF is deenergized, the polar contacts remain in the position to which they are moved due to the energization of relay CF during the on code period. That is to say, the polar contacts of relay CF closed at the start of a code remain 40 closed as long as that code persists.

A decoding transformer DT is supplied with current in step with the operation of relay CF from a convenient source of direct current such as a battery, not shown, but whose terminals are indicated at B and C. The two half portions of primary winding 25 of transformer DT are alternately connected with the B and C terminals of the current source over front contact 11 and back contact 14 of relay CF. When relay CF is picked up closing front contact 11, current flows in the top portion of primary winding 25 and magnetic flux builds up in one direction in magnetic core 26 of transformer DT. When relay CF is released to open front contact 11 and close back contact 14 the current to the top portion of primary winding 25 is interrupted and current flows in the lower portion of winding 25 and the magnetic flux of core 26 dies down, passes through zero and builds up in the other direction due to such change in the flow of current in primary winding 25. When relay CF is picked up to open back contact 14 and close front contact 11, a corresponding change takes place in the current supplied to primary winding 25 and a corresponding variation of the magnetic flux in core 26 is effected except the relative directions of the current and magnetic flux are opposite to those effected when the relay is released. Each such variation or reversal of the magnetic flux of core 70 26 creates an electromotive force in secondary

winding 27 of transformer DT. The value of such electromotive force is within limit proportional to the density of the magnetic flux, since the rate of change is substantially the same for both pick-up and release operations of relay CF. The transformer DT and its charging circuit are proportioned to effect substantially magnetic saturation of core 26 during a one-fourth second period which is the duration of the short code period of the track circuit current. It follows that the electromotive force induced in secondary winding 27 is substantially the same whether relay CF is operated in step with the short code period of one-fourth second duration or in step with the long code period of one and one-half seconds 15 duration. The time interval between successive electromotive forces induced in secondary winding 27 is substantially the code period duration at which relay CF is operated. In other words when relay CF is operated at the high code rate 20 the interval between successive electromotive forces induced in secondary winding 27 is substantially one-fourth second and when relay CF is operated at the low code rate the interval between successive electromotive forces is substantially 25 one and one-half seconds.

A decoding relay D is connected with secondary winding 27 for energization of that relay by the electromotive forces induced in winding 27. Preferably winding 28 of relay D is connected with the top and lower portions of secondary winding 27 over front contact 12 and back contact 15 of relay CF so that the electromotive forces are rectified and unidirectional current impulses are supplied to winding 28. Relay D is adjusted for 30 a predetermined pick-up energization. The winding 28 of relay D and the secondary winding 27 of transformer DT are proportioned so that when the electromotive forces induced in secondary winding 27 are spaced apart about one-fourth 35 second the energization of relay D is gradually built up and after a few such electromotive forces the pick-up energization of relay D is effected and relay D is picked up. Relay D is preferably 40 slightly slow to release so that it does not release 45 when the successive electromotive forces are spaced apart one-fourth second. However, when the electromotive forces are spaced apart one and one-half seconds the energization of relay D effected by each electromotive force dies away before the next following electromotive force appears and relay D remains deenergized or at least 50 its energization does not build up to a value sufficient to pick up the relay. It follows that when relay CF is operated at the high code rate decoding relay D is picked up but that when relay CF is operated at the low code rate decoding relay 55 D is released.

To further check operation of code following relay CF by coded current, two slow release relays FSA and BSA are provided and controlled over neutral contacts of the code following relay CF. Relay FSA is governed over a simple circuit including front contact 13 of relay CF and relay BSA is governed over a circuit including back contact 16 of relay CF and front contact 29 of relay FSA as will be readily understood by an inspection of Fig. 1. Consequently these two relays FSA and BSA are energized and retained picked up only when relay CF is operated to alternately 60 close front contact 13 and back contact 16, relays FSA and BSA being provided with slow release periods sufficient to bridge the long code period referred to hereinbefore.

The decoding relay D and polar contacts of 75

- relay CF selectively control the operative circuits of a wayside signal WS which governs traffic through section W—X, such signal operating circuits being also governed by check relay BSA. 5
- In a similar manner, decoding relay D, check relay BSA and polar contacts of relay CF are used to control the supply of coded current to the track circuit for the section next in the rear of section W—X. That is to say that in order to 10 reflect different traffic conditions in advance of such section next in the rear, the track circuit current for that section is controlled by relays D, BSA and CF associated with section W—X, such current being coded by one or the other of two 15 coding devices 20CT and 120CT.

The coding devices or code transmitters 20CT and 120CT may be any one of several types of coding devices and as shown are of the relay type provided with a code contact element or member 20 which is operated in a cyclic manner as long as the operating winding of the code transmitter is supplied with current from any convenient source such as the battery whose terminals are indicated as B and C. Code transmitter 20 is 25 portioned so that its code contact element or member 30 is operated at the rate of 20 cycles per minute or 1 operation cycle every three seconds. The arrangement is such that contact member 30 is raised to engage a contact 31 during 30 substantially one-half of each operation cycle and is lowered to break engagement with contact 31 for substantially one-half of the operation cycle. Hence contact 30—31 is closed for a period of one and one-half seconds and is open for a period of 35 one and one-half seconds each operation cycle of the code transmitter. The code transmitter 120CT is similar in construction except its contact member 32 is operated at the rate of 120 cycles per minute or 2 operation cycles per second, contact member 32 being raised to engage a contact 33 for one-half of each operation cycle and lowered to disengage contact 33 for one-half of each 40 operation cycle. As will shortly appear, contact member 30 of code transmitter 20CT is used to 45 create long code periods and contact member 32 of code transmitter 120CT is used to create short code periods.

The wayside signal FS may be any standard 50 type of signal and as shown is a color light signal capable of displaying five different signal indications. It is believed that the operating circuits for signal WS, as well as the circuits for supplying coded current to the track circuit next in the rear of section W—X can best be understood by a description of the operation of the apparatus.

It is to be observed that relay XR and relay XP are controlled by the apparatus associated with the section next in advance of section W—X in 60 the same manner that relays WR and FP for the section next in the rear of section W—X are controlled by the apparatus associated with the track circuit of the section W—X.

I shall first assume that a train occupies section W—X to shut the track circuit so that code following relay CF is inactive with its back neutral contact closed. Under this condition decoding relay D is deenergized and released because no electromotive forces are induced in secondary winding 27 of transformer DT, and check relays FSA and BSA are deenergized and released because relay CF is inactive. With relay BSA released an operating circuit can be traced from terminal B of the current source over back contact 34 of relay BSA, lamp R of the top group of lamps of

signal WS and terminal C, and lamp R is illuminated. Also an operating circuit extends from terminal B over back contact 35 of relay BSA, lamp R of the lower group of lamps of signal WS and to terminal C, and this lamp R is also illuminated so that signal WS displays a red lamp above a red lamp for a stop signal indication. 5

The control circuit for relay WP is now open at both front contact 36 of relay D and front contact 37 of relay BSA, as will be apparent by an inspection of Fig. 1 and relay WP is released to close its back pole changing contacts 42 and 43. Relay WR is provided with a circuit including terminal E, contact 30—31 of code transmitter 20CT, back contact 38 of relay BSA, winding of relay WR 15 and to terminal C, and relay WR is operated in step with operation of contact member 30. Since relay WP is released and relay WR operated at the code rate of 20 cycles per minute the track circuit current of the section next in the rear 20 of section W—X is coded according to the approach code of Fig. 2 when the train occupies section W—X.

I shall next assume that the train moves to the right out of section W—X and occupies the section next in advance. The relay XP is released and relay XR is operated at the rate of 20 cycles per minute, it being recalled that relays XR and XP are controlled by the apparatus for the section next in advance in the same manner that 25

relays WP and WR are controlled by the apparatus of section W—X. With relay XP released and relay XR operated at the rate of 20 cycles per minute, the track circuit current of section W—X is coded at the approach code and code following 35

relay CF operates its neutral contact members at a corresponding rate and moves its polar contact members to the reverse or right-hand position as viewed in Fig. 1. Relays FSA and BSA are picked up in response to such code operation of relay CF 40 but decoding relay D remains released because of the long interval between successive electro-motive forces induced in secondary winding 27 of transformer DT. With relay BSA picked up and relay D released and the reverse polar contacts of 45 relay CF closed, an operating circuit can be traced from terminal B over front contact 39 of relay BSA, reverse polar contact 24 of relay CF, lamp Y of the top group of lamps of signal WS and to terminal C, and this lamp Y is illuminated. Also 50 an operating circuit extends from terminal B over front contact 40 of relay BSA, reverse polar contact 22 of relay CF, back contact 41 of relay D, lamp R of the lower group of lamps of signal WS and to terminal C, and lamp R is illuminated so 55 that signal WS displays a yellow light over a red light for an approach signal indication. The circuit for relay WP is open the same as before and this relay is released closing back contacts 42 and 43. Relay WR is controlled over a circuit involving terminal B, contact 32—33 of code transmitter 120CT, back contact 44 of relay D, reverse polar contact 21 of relay CF, front contact 45 of relay BSA, winding of relay WR and terminal C, and 60 relay WR is operated at the rate of 120 cycles per minute so that the track circuit current for the section next in the rear is coded at the approach-slow code of Fig. 2 when section W—X is unoccupied and a train occupies the section next 65 in advance of section W—X.

Assuming next that the train advances one more section to the right to occupy the second section in advance of section W—X and the first section in advance is unoccupied, the relay XP is released and relay XR is operated at the rate 75

of 120 cycles per minute so that the track circuit current of section W—X is of the approach-slow code. Code following relay CF now operates its neutral contact members at the rate of 120 cycles per minute and its polar contact members are still retained at the reverse position. Relays FSA and BSA are picked up by the code operation of relay CF and decoding relay D is picked up because the electromotive forces induced in secondary winding 27 are spaced apart only one-fourth second. Under this condition of the relays an operating circuit is provided for lamp Y of the top group of lamps of signal WS the same as before and another operating circuit extends from terminal B over front contact 40 of relay BSA, reverse polar contact 22 of relay CF, front contact 46 of relay D, lamp Y of the lower group of lamps and to terminal C, and this lamp is illuminated so that signal WS displays a yellow light over a yellow light for an approach-slow signal indication. The circuit for relay WP is now closed at front contact 36 of relay D and relay WP is picked up to close its front pole changing contacts 47 and 48. Relay WR is controlled over a circuit that can be traced from terminal B, contact 30—31 of code transmitter 28CT, front contact 49 of relay D, reverse polar contact 21 of relay CF, front contact 45 of relay BSA, winding of relay WR and to terminal C, and relay WR is operated at the rate of 20 cycles per minute. Hence the track circuit current for the section next in the rear is coded at the approach-medium code of Fig. 2 when there are two unoccupied sections in advance and the third section in advance is occupied.

Assuming that the train moves another section to the right to occupy the third section in advance of section W—X, leaving the two sections next in advance of section W—X unoccupied, the relay XP is picked up and relay XR is operated at the rate of 20 cycles per minute, it being again recalled that relays XR and XP are controlled in the same manner as relays WR and WP. With relay XP picked up and relay XR operated at the rate of 20 cycles per minute the track circuit current is of the approach-medium code and relay CF operates its neutral contact carrying armature at the corresponding rate and positions its polar contact carrying armature at the normal or left-hand position as viewed in Fig. 1. Relays FSA and BSA are picked up the same as before, but decoding relay D is released because of the long time interval between the successive electromotive forces induced in secondary winding 27 of transformer DT. Under this condition of the relays an operating circuit for lamp Y of the top group of lamps is completed from terminal B over front contact 39 of relay BSA, normal polar contact 20 of relay CF, back contact 50 of relay D, lamp Y and to terminal C. Also an operating circuit is formed for lamp G of the lower group of lamps, from terminal B, over front contact 48 of relay BSA, normal polar contact 13 of relay CF, lamp G and to terminal C. Thus signal WS displays a yellow light over a green light for an approach-medium signal indication. The circuit for relay WP is now closed at normal polar contact 19 of relay CF and front contact 37 of relay BSA so that relay WP is picked up. Relay WR is controlled by a circuit formed from terminal B, over contact 32—33 of code transmitter 120CT, normal polar contact 17 of relay CF, front contact 45 of relay BSA, winding of relay WR and to terminal C, and relay WR is operated at the rate of 120 cycles per minute

so that the track circuit current of the associated section is coded at the clear code of Fig. 2 when there are three unoccupied sections next in advance.

Again assuming the train advances another section to the right leaving three sections in advance of section W—X unoccupied, relay XP is picked up and relay XR is operated at the rate of 120 cycles per minute to provide a clear code for the track circuit current of section W—X. Relay CF is operated at a corresponding rate and its polar contact carrying armature is retained at the normal position. This rate of operation of relay CF is effective to cause relays FSA, BSA and D to be all picked up. An operating circuit is now formed for the G lamp of the top group of lamps from terminal B over front contact 39 of relay BSA, normal polar contact 20 of relay CF, front contact 51 of relay D, lamp G and to terminal C. A second operating circuit is formed from terminal B over front contact 40 of relay BSA, normal polar contact 13 of relay CF, lamp G of the lower group of lamps and to terminal C, and signal WS displays a green light over a green light for a clear signal indication. Circuits for relays WP and WR are formed the same as before and the track circuit current of the associated section is still coded at the clear code.

It is apparent that with the decoding transformer DT proportioned for magnetic saturation at the short code periods the usual variations caused by variations of voltages of the current source creates little if any variation in the electromotive force induced in secondary winding 27. Furthermore, since the difference between the short and long code periods is relatively large a correspondingly large difference exists in the spacing of the electromotive forces induced in secondary winding 27 so that the usual variations in the operating characteristics of the decoding relay D and transformer DT due to changes in the resistances of the windings of these devices because of changes in temperature do not effect the selective control of relay D to an extent that requires special compensating devices.

While I have disclosed my invention as used to provide four different codes for a four-block five-indication signal system, it is contemplated that the invention may be used to provide three different codes for a three-block four-indication signal system leaving the fourth code to be used for some special control such as the control of a highway crossing signal, if desired. Again, two codes may be used to effect a two-block three-indication signal system leaving two codes for special controls, if desired.

Although I have herein shown and described only one form of railway traffic controlling apparatus embodying my invention, it will be understood that various changes and modifications may be made therein within the scope of the appended claims without departing from the spirit and scope of my invention.

Having thus described my invention, what I claim is:

1. In railway traffic controlling apparatus for use with a track circuit supplied at times with current of positive polarity coded at a pre-selected code rate and at other times with current of negative polarity coded at said pre-selected code rate for operating the neutral contact carrying armature of a polarized code following relay connected with said circuit at said code rate and for positioning the polar contact carrying armature at a normal or a reverse posi-

tion according to the polarity of such coded current, the combination comprising, a decoding relay, an impedance element, circuit means including said impedance element and a contact 5 of said neutral armature to energize said decoding relay and said circuit means proportioned to effectively energize the decoding relay to pick up the relay only when said code following relay is operated at said preselected code rate, and signaling circuits selectively controlled over contacts of said decoding relay and normal and reverse contacts of said polar armature.

2. In railway traffic controlling apparatus for use with a track circuit supplied at times with 15 current of positive polarity coded at a pre-selected code rate and at other times with current of negative polarity coded at said pre-selected code rate for operating the neutral contact carrying armature of a polarized code following relay connected with said circuit at said 20 code rate and for positioning the polar contact carrying armature at a normal or a reverse position according to the polarity of such coded current, the combination comprising, a decoding 25 transformer, a decoding relay, circuit means including a front and a back contact of said neutral armature to alternately supply direct current to two portions of a primary winding of said transformer to induce electromotive forces 30 in a secondary winding of the transformer at a rate corresponding to said code rate, other circuit means including another front and back contact of said neutral armature to connect said secondary winding to a winding of said decoding 35 relay to energize the decoding relay by said electromotive forces, said secondary winding and said decoding relay winding proportioned to build up the energization of the decoding relay sufficient to pick up that relay only when said 40 electromotive forces are of a rate at least equal to that corresponding to said code rate, and signaling circuits selectively controlled over contacts of said decoding relay and normal and reverse contacts of said polar armature.

45 3. In railway traffic controlling apparatus for use with a track circuit supplied with coded current at times of positive polarity and at other times of negative polarity and which code has a cyclic pattern of one on and one off period of 50 equal preselected durations and to which circuit is connected a polarized code following relay for operating a neutral contact member in step with the code periods and for positioning a polar contact member at a normal or a reverse position 55 according to the polarity of the coded current, the combination comprising, a decoding transformer, circuit means including said neutral contact member to supply direct current to a primary winding of said transformer to induce in 60 a secondary winding of the transformer electromotive forces spaced apart by intervals substantially equal to the duration of said code periods, a decoding relay having a winding connected to said secondary winding for energization of the 65 relay by said electromotive forces and said decoding relay proportioned so that the energization builds up sufficiently to pick up the decoding relay only when the electromotive forces are spaced apart by intervals not greater than said 70 code period duration, a first signaling circuit including a front contact of said decoding relay and said polar contact member at its normal position, and a second signaling circuit including a front contact of said decoding relay and said 75 polar contact member at its reverse position.

4. In railway traffic controlling apparatus for use with a track circuit supplied with coded current at times of positive polarity and at other times of negative polarity and which code has a cyclic pattern of one on and one off period of 5 equal preselected durations and to which circuit is connected a polarized code following relay for operating a neutral contact carrying armature in step with the code periods and for positioning a polar contact carrying armature according to 10 the polarity of the coded current, the combination comprising, a decoding transformer, circuit means including a front and a back contact of said neutral armature to alternately supply direct current to two portions of a primary winding of said transformer to induce in a secondary winding of the transformer an electromotive force at intervals substantially equal to said code period duration, a decoding relay, other circuit means including a front and a back contact of said neutral armature to connect said secondary winding to a winding of said decoding relay for energization of that relay by unidirectional current impulses spaced apart by intervals corresponding to said code period duration, said decoding 15 relay characterized by its energization building up sufficiently to pick up the relay only when said current impulses occur at intervals not greater than said code period duration, a first signaling circuit including a front contact of said decoding relay and a normal contact of said polar armature, and a second signaling circuit including a front contact of said decoding relay and a reverse contact of said polar armature.

5. In railway traffic controlling apparatus for use with a track circuit supplied at times with coded current of a predetermined low code rate and at other times with coded current of a predetermined high code rate for operating a code 40 following track relay at a rate corresponding to the code rate of the track circuit current, the combination comprising, a decoding transformer having a preselected magnetic core, a charging circuit including a front contact of said code following relay to connect a source of direct current to a primary winding of said transformer to periodically create a magnetic flux in said core and induce in a secondary winding of the transformer electromotive forces having a rate of occurrence corresponding to the code rate at which said code following relay is operated, said charging circuit proportioned to effect magnetic saturation of said magnetic core during a code 45 period of said high code rate and electromotive forces of substantially the same value are induced in the secondary winding for both code rates, a decoding relay, rectifying means to connect said secondary winding to a winding of said decoding relay to energize the decoding relay by unidirectional current impulses created by said electromotive forces, said decoding relay characterized by the building up of its energization sufficient to pick up the relay when such current impulses occur at a rate corresponding to said high code rate but not to said low code rate, and a signaling device distinctive to said high code rate controlled over a front contact of said decoding relay.

6. In railway traffic controlling apparatus for use with a track circuit supplied at times with coded current of a predetermined low code rate and at other times with coded current of a predetermined high code rate for operating a code following track relay at a rate corresponding to the code rate of the track circuit current, the 70 75

combination comprising, a decoding transformer having a preselected magnetic core, a charging circuit including a front contact of said code following relay to connect a source of direct current to a primary winding of said transformer to periodically create a magnetic flux in said core and induce in a secondary winding of the transformer electromotive forces having a rate of occurrence corresponding to the code rate at which said code following relay is operated, said charging circuit proportioned to effect magnetic saturation of said magnetic core during a code period of said high code rate and electromotive forces of substantially the same value are induced in the secondary winding for both code rates, a decoding relay, circuit means including a contact of said code following relay to connect said secondary winding to a winding of said decoding relay to supply an energizing current impulse to said decoding relay in response to each of said electromotive forces, said secondary winding and decoding relay winding proportioned as to their impedances so that the energization of the decoding relay builds up sufficiently to pick up that relay when the electromotive forces are of the rate corresponding to said high code rate but not to said low code rate, and a signaling device distinctive to said high code rate controlled over a front contact of said decoding relay.

7. In railway traffic controlling apparatus for use with a track circuit supplied at times with coded current of a predetermined low code rate and at other times with coded current of a predetermined high code rate for operating a code following track relay at a rate corresponding to the code rate of the track circuit current, the combination comprising, a decoding transformer having a preselected magnetic core, a charging circuit including a front contact of said code following relay to connect a source of direct current to a primary winding of said transformer to periodically create a magnetic flux in said core and induce in a secondary winding of the transformer electromotive forces having a rate of occurrence corresponding to the code rate at which said code following relay is operated, said charging circuit proportioned to effect magnetic saturation of said magnetic core during a code period of said high code rate and electromotive forces of substantially the same value are induced in the secondary winding for both code rates, a decoding relay, circuit means including a contact of said code following relay to connect said secondary winding to a winding of said decoding relay to supply an energizing current impulse to said decoding relay in response to each of said electromotive forces, said secondary winding and decoding relay winding proportioned as to their impedances so that the energization of the decoding relay builds up sufficiently to pick up that relay when the electromotive forces are of the rate corresponding to said high code rate but not to said low code rate, another relay, circuit means including a front and a back contact of said code following relay to effectively energize said other relay when the code following relay is operated, and signaling circuits selectively controlled by said decoding relay and said other relay.

8. In railway traffic controlling apparatus for use with a track circuit supplied at times with current of positive polarity coded at either a predetermined high or low code rate and at other times with current of negative polarity coded at either said high or said low code rate, the com-

bination comprising, a polarized code following relay connected to said track circuit for operation of a neutral contact carrying armature at a rate corresponding to the code rate of the track circuit current and to position a polar contact carrying armature at a normal or a reverse position according to the positive or negative polarity of said current, a decoding transformer having a magnetic core, a charging circuit including a contact of said neutral armature to supply direct current to a primary winding of said transformer to induce electromotive forces in a secondary winding of the transformer at a rate corresponding to the rate at which said code following relay is operated, said charging circuit and transformer proportioned to effect magnetic saturation of said magnetic core during the code period of said high code rate to induce electromotive forces of substantially equal value for both said code rates, a decoding relay having a winding connected to said secondary winding, said relay winding and said secondary winding proportioned to build up an energization sufficient to pick up said decoding relay in response to electromotive forces of the rate corresponding to said high code rate but not to said low code rate, and signaling circuits selectively controlled over contacts of said decoding relay and normal and reverse contacts of said polar armature.

9. In railway traffic controlling apparatus for use with a track circuit supplied at times with current of positive polarity coded at either a predetermined high or low code rate and at other times with current of negative polarity coded at either said high or said low code rate, the combination comprising, a polarized code following relay connected to said track circuit for operation of a neutral contact carrying armature at a rate corresponding to the code rate of the track circuit current and to position a polar contact carrying armature at a normal or a reverse position according to the positive or negative polarity of said current, a decoding transformer having a magnetic core, a charging circuit including a contact of said neutral armature to supply direct current to a primary winding of said transformer to induce electromotive forces in a secondary winding of the transformer at a rate corresponding to the rate at which said code following relay is operated, said charging circuit and transformer proportioned to effect magnetic saturation of said magnetic core during the code period of said high code rate to induce electromotive forces of substantially equal value for both said code rates, a decoding relay, circuit means including a front and a back contact of said neutral armature to connect said secondary winding to a winding of said decoding relay to supply unidirectional current impulses to the decoding relay at a rate corresponding to the rate of the electromotive force, said decoding relay characterized by the building up of its energization sufficient to pick up that relay when such current impulses have a rate corresponding to said high code rate but not to said low code rate, and signaling circuits selectively controlled over contacts of said decoding relay and normal and reverse contacts of said polar armature.

10. In railway traffic controlling apparatus for use with a track circuit supplied at times with current of positive polarity coded at either a predetermined high or low code rate and at other times with current of negative polarity coded at either said high or said low code rate, the combination comprising, a polarized code following re-

- lay connected to said track circuit for operation of a neutral contact carrying armature at a rate corresponding to the code rate of the track circuit current and to position a polar contact carrying armature at a normal or a reverse position according to the positive or negative polarity of said current, a decoding transformer having a magnetic core, a charging circuit including a contact of said neutral armature to supply direct current to a primary winding of said transformer to induce electromotive forces in a secondary winding of the transformer at a rate corresponding to the rate at which said code following relay is operated, said charging circuit and transformer proportioned to effect magnetic saturation of said magnetic core during the code period of said high code rate to induce electromotive forces of substantially equal value for both said code rates, a decoding relay having a winding connected with said secondary winding, said relay winding and said secondary winding proportioned to building up energization sufficient to pick up said decoding relay in response to electromotive forces of the rate corresponding to said high code rate but not to said low code rate, another relay, circuit means including a front and a back contact of said neutral armature operative to energize said other relay when the code following relay is operated at either said high or low code rate, and signaling circuits selectively controlled over contacts of said decoding relay and said other relay as well as normal and reverse contacts of said polar armature.
11. In combination, a stretch of railway track divided into a plurality of consecutive track sections each provided with a track circuit, transmitting means for a given section for supplying to the track circuit of said given section direct current of negative polarity coded at a predetermined low rate, or of negative polarity coded at a predetermined high rate, or direct current of positive polarity coded at said low rate or of positive polarity coded at said high rate according to a first, a second, a third or a fourth traffic condition in advance of said given section, a polarized code following relay connected to said track circuit to operate a neutral contact carrying armature at the code rate of the track circuit current and to position a polar contact carrying armature according to the polarity of the current, a decoding transformer, a decoding relay, circuit means including contacts of said neutral armature and said transformer to energize said decoding relay and operative to pick up the decoding relay in response to track circuit current coded at said high rate but not said low rate, another relay, circuit means including contacts of said neutral armature effective to energize said other relay in response to track circuit current of either of said code rates, a signal having a distinctive indication for each of said four mentioned traffic conditions, and an operating circuit for each of said signal indications selectively controlled over contacts of said decoding relay, said other relay and contacts of said polar armature.
12. In combination, a section of railway track, traffic governed means operative for supplying to the rails of said section direct current of negative polarity coded at a preselected low code rate or at a preselected high code rate or direct current of positive polarity coded at said low code rate or at said high code rate according to four different traffic conditions in advance of said sec-

tion, a polarized code following track relay connected to the rails of said section for operating its neutral armature at the code rate of such current supplied to the rails and for positioning its polar armature according to the polarity of such current, a decoding transformer having a magnetic core, a charging circuit including a front and a back contact of said track relay to supply direct current to a primary winding of said transformer and proportioned to create magnetic saturation of said core at said high code rate to induce in a secondary winding of said transformer electromotive forces of a rate corresponding to the code rate at which said track relay is operated but of substantially uniform value, a decoding relay connected to said secondary winding over a front and a back contact of said track relay to energize the decoding relay by unidirectional current impulses created by said electromotive forces and said decoding relay characterized by the building up of its energization sufficient to pick up that relay only when said track relay is operated at said high code rate, a signal for said section capable of displaying a distinctive indication for each of said four traffic conditions, and four operating circuits one for each of said signal indications selectively controlled by said decoding relay and polar contacts of said track relay.

13. In combination, a section of railway track, traffic governed means operative for supplying to the rails of said section direct current of negative polarity coded at a preselected low code rate or at a preselected high code rate or direct current of positive polarity coded at said low code rate or at said high code rate according to four different traffic conditions in advance of said section, a polarized code following track relay connected to the rails of said section for operating its neutral armature at the code rate of such current supplied to the rails and for positioning its polar armature according to the polarity of such current, a decoding transformer having a magnetic core, a charging circuit including a front and a back contact of said track relay to supply direct current to a primary winding of said transformer and proportioned to create magnetic saturation of said core at said high code rate to induce in a secondary winding of said transformer electromotive forces of a rate corresponding to the code rate at which said track relay is operated but of substantially uniform value, a decoding relay connected to said secondary winding over a front and a back contact of said track relay to energize the decoding relay by unidirectional current impulses created by said electromotive forces and said decoding relay characterized by the building up of its energization sufficient to pick up that relay only when said track relay is operated at said high code rate, another relay, circuit means including a front and a back contact of said track relay effective to pick up said other relay when said track relay is operated at either said low or high code rate, a signal for said section capable of displaying a distinctive proceed indication of each of said four traffic conditions and a fifth stop indication, and five operating circuits one for each of said five signal indications selectively controlled over contacts of said decoding relay and said other relay and polar contacts of said track relay.
